CLAIM

The ornamental design for a primary package for a solid,
single dose beauty care composition, as shown and
described.

DESCRIPTION

FIG. 1 is a first perspective view of a primary package for
a solid, single dose beauty care composition, embodying our
new design;

FIG. 2 is a second perspective view of the primary package
of FIG. 1;

FIG. 3 is a front view of the primary package of FIG. 1;
FIG. 4 is a back view of the primary package of FIG. 1;
FIG. 5 is a first side view of the primary package of FIG. 1;
FIG. 6 is a second side view of the primary package of FIG.
1;

FIG. 7 is a third side view thereof of the primary package of
FIG. 1; and,

FIG. 8 is a fourth side view of the primary package of FIG.
1.

In the drawings, the evenly-spaced broken lines show por-
tions of the primary package for a solid, single dose beauty
care composition that form no part of the claim; the dash-
dot-dot lines represent boundaries of the claimed design
and form no part thereof.
